[57] CLAIM

The ornamental design for a planting tool, as shown and described.

DESCRIPTION

FIG. 1 is an environmental perspective view of the planting tool in an opened position;

FIG. 2 is an environmental perspective view thereof in a closed position;

FIG. 3 is a front elevational view of the planting tool in the closed position, the rear elevational view being a mirror image of the front view;

FIG. 4 is a right side elevational view thereof, the left side view being a mirror image of the right side view;

FIG. 5 is a top plan view thereof; and,

FIG. 6 is a bottom plan view thereof.

The broken line showing of earth, plants and a human hand are for illustrative purposes only and form no part of the claimed design.
